UNITED STATES PATENT OFFICE

LEE S. POPE, OF GREENSBORO, NORTH CAROLINA

ALTERNATING REFRIGERATION BOTTLED DRINK COOLER

Application filed October 6, 1928. Serial No. 310,781.

This invention relates to refrigerators, and more particularly to devices of this character that are especially adapted to be used for the purpose of chilling bottled goods such as soft 5 drinks.

The invention has for one of its objects to provide a device of the character stated which shall be adapted to effect the rapid chilling of the bottled goods in a manner to permit 10 them to be removed therefrom with the bottles in a dry condition, whereby to overcome the disadvantages of and the distastes to the present method of chilling bottled goods which consists in placing the bottled goods 15 in water chilled by ice.

A further object of the invention is to provide a device of the character stated which shall embody tanks surrounded by a refrigerating brine and a motor operated refrigerating unit having an expansion coil arranged in the brine.

A further object of the invention is to provide a device of the character stated wherein the tanks shall be provided with compartments 25 adapted for dry chilling and the remainder for wet chilling, whereby to permit the chilling of goods of that kind not adapted for immersion and that kind adapted for immersion.

30 A further object of the invention is to provide a device of the character stated which shall embody means through the medium of which one of the tanks may be flooded with water, whereby to adapt one tank for dry 35 chilling and the other for wet chilling.

A further object of the invention is to provide a device of the character stated which shall embody means through the medium of which one tank may be flooded with water 40 and the water, after being chilled and chilling the bottled goods immersed therein, withdrawn from the tank and forced into the other tank, whereby to permit the rapid 45 chilling of the bottled goods in a manner to permit them to be withdrawn from the device in a dry state.

A still further object of the invention is to provide a device of the character stated which 50 shall be simple, durable and capable of being

manufactured and sold and operated at a low cost.

With the foregoing and other objects in view, the nature of which will appear as the description proceeds, the invention consists 55 in the construction, combination and arrangement of parts hereinafter fully described and claimed, and illustrated in the accompanying drawings, wherein:

Figure 1 is a view partly in top plan and 60 partly in horizontal section of a refrigerator constructed in accordance with my invention;

Figure 2 is a sectional view taken on the vertical planes indicated by the line 2—2 of 65 Figure 1;

Figure 3 is a sectional view taken on the vertical planes indicated by the line 3—3 of Figure 1;

Figure 4 is a bottom plan view of the refrigerator; 70

Figure 5 is a sectional view taken on the vertical plane indicated by the line 5—5 of Figure 2;

Figure 6 is a sectional view taken on the vertical plane indicated by the line 6—6 of 75 Figure 2, and

Figure 7 is sectional view taken on the horizontal plane indicated by the line 7—7 of Figure 2.

The refrigerator comprises a box or body 80 1 which may be square or oblong in plan and of any desired or required size. The box 1 which may be made from wood or metal or any other suitable material, embodies bottom, side, end and top walls, and is supported by 85 feet 2. The box 1 is provided on the interior thereof with a thick layer 3 of cork board to insulate the interior from the surrounding atmosphere, and it is provided with a metal lining 4 to adapt it for the reception of a refrigerating brine. 90

Tanks 5 having a plan contour similar to that of the box and made from metal are arranged within the box and rest upon the bottom wall thereof. The tanks 5 are fully 95 open at their upper sides, and their upper portions are arranged in openings 6 formed in the top wall of the box 1. The upper portions of the sides and ends of the tanks 5 contact with the walls of the openings 6 to 100

effect the closing of the box 1 about the openings. The tanks 5 are spaced from each other and from the side and end walls of the box 1 to permit them to be completely surrounded by the brine. The expansion coil 7 of a motor operated refrigerating unit is arranged in the box 1 between the tanks 5, the ends of the coil extending through and beyond one of the end walls of the box. As the refrigerating unit may be any of the well known types now on the market, it is believed that it is unnecessary to describe or illustrate the other parts of the unit.

The tanks 5 are separated into compartments by metal partitions which extend from the bottom to the top and from one side to the other of the tanks. One or more of the compartments of each tank are dry and the remainder are wet, the dry compartments being designated 8 and the wet compartments 9. The partitions 10 which provide the dry compartments 8 are imperforate. The remaining partitions 11 are perforated to permit water supplied to one of the compartments 9 to flow into the remaining of these compartments, and to permit the water to be drained from all of these compartments by way of one of them. The compartments 8 and 9 are provided with insulated covers 12 which rest upon flanges 13 within the upper sides of the compartments and which are provided with handles 14.

Pipes 15 are arranged below and extend longitudinally of the box 1, each of which communicates at its inner end with one of the compartments 9 of each tank 5, as shown at 16. The outer ends of the pipes 15 are connected by a pipe 17, and are provided inwardly of the connecting pipe with cut-off valves 18 and 19. A pipe 20 provided with a cut-off valve 21 and extending from a source of water supply, communicates with one of the pipes 15 and with the connecting pipe 17. The connecting pipe 17 is provided with a drain cock 22. Pipes 23 are also arranged below and extend longitudinally of the box 1, each of which communicates at its inner end with one of the compartments 9 of each tank 5, as shown at 24. The pipes 23 are connected at their outer ends by a pipe 25, and are provided inwardly of the connecting pipe with cut-off valves 26 and 27. One of the pipes 23 is connected by a pipe 28 with the intake port of a rotary pump 29, the discharge port of the pump being connected by a pipe 30 to the pipe 17. An electric motor 31 is provided for operating the pump 29.

These pipes and pump constitute means through the medium of which the compartments 9 of one of the tanks 5 may be flooded with water, through the medium of which the chilled water in the compartments 9 of one tank may be drawn therefrom and forced into the corresponding compartments of the other tank, and through the medium of which the

water may be drawn from the flooded compartments. To provide the compartments 9 of one of the tanks 5 with water it is only necessary to open the valve 21 and one of the valves 18 and 19. After the compartments 70 have been supplied with the desired amount of water the valve 21 is closed. After the water has been chilled and has chilled the contents of the bottles to the desired degree, the valve in that pipe 15 communicating with the flooded compartments 9 is closed, the valve in that pipe 23 communicating with these compartments is opened, the valve in the other pipe 15 which communicates with the compartments 9 of the other tank 5 is 75 opened, and the pump 29 is operated, with the result that the chilled water will be withdrawn from the flooded compartments 9 of one tank and forced into the compartments 9 of the other tank. While bottled goods are 80 being chilled in the flooded compartments 9 of one tank, bottled goods are being chilled in the now dry compartments 9 of the other tank. After the withdrawal of the water from said first compartments and its discharge to said second compartments, and during the chilling of the bottled goods by the water in said second compartments, the bottles in said first compartments are subjected to a drying action. This method permits the bottled goods to be quickly chilled and delivered to the purchaser with bottles 85 in a dry state.

This method of chilling goods is used during those days when business is good. When 100 business is slack, the bottled goods may be cooled without using water in the compartments 9. The bottles are arranged in the compartments with their bottoms in contact with the sides of the tanks 5, as illustrated, 105 and due thereto their contents will be chilled to the desired degree slower than when water is employed but rapidly enough to serve the trade during dull days.

After the bottled goods have been chilled 110 by the water and the water withdrawn, they will maintain their chilled temperature for an indefinite period due to the fact that the tanks are surrounded by the chilled brine which is maintained at freezing temperature by the refrigerating unit.

A pipe 32 provides means for supplying the box 1 with brine, and a cock 33 permits the brine to be drawn off from the box.

In the event that the refrigerating unit 120 should fail to operate, the bottled goods will be maintained at a chilled temperature for a considerable period of time due to the low temperature of the brine and to the insulation of the brine and tanks from the surrounding atmosphere.

From the foregoing description, taken in connection with the accompanying drawings, the advantages of the construction and the method of operation will be readily ap- 130

parent to those skilled in the art to which the invention appertains. While I have described the principle of operation of the invention, together with the device which I now consider to be the best embodiment thereof, I desire to have it understood that the device shown is merely illustrative, and that such changes may be made when desired as are within the scope of the invention and claimed.

What I claim is:

1. A refrigerator comprising a box adapted to contain brine, a refrigerating unit expansion coil in the box, tanks arranged in the box dipping into the brine, means for supplying the tanks with water and means for withdrawing the water from one tank and forcing it into the other.
2. A refrigerator comprising a box adapted to contain brine, a refrigerating unit expansion coil in the box, tanks arranged in the box and dipping into the brine, each of said tanks embodying a dry refrigerating compartment and a moist refrigerating compartment, means for supplying water to the moist refrigerating compartment of one tank and thereafter removing it from said compartment and discharging it into the corresponding compartment of the other tank.
3. A refrigerator comprising tanks, refrigerating units for said tanks, and means for supplying one of the tanks with water and thereafter simultaneously withdrawing the water from said tank and discharging it into the other tank, as and for the purposes set forth.

In testimony whereof I affix my signature.

LEE S. POPE.
